(57) **CLAIM**

The ornamental design for a heavy duty hanger, as shown and described.

DESCRIPTION

FIG. 1 is a perspective view of a heavy duty hanger, showing my new design;

FIG. 2 is a back elevational view thereof, with the opposite side being a mirror image of that shown in FIG. 2;

FIG. 3 is a top plan view thereof;

FIG. 4 a bottom plan view thereof;

FIG. 5 is a side elevational view of the left side of FIG. 2; and,

FIG. 6 is a side elevational view of the right side of FIG. 2.
